UNITED STATES PATENT OFFICE.

STEWART E. SEAMAN, OF BROOKLYN, NEW YORK.

APPARATUS FOR THE DESTRUCTIVE DISTILLATION OF WOOD.

1,115,590.

Specification of Letters Patent.

Patented Nov. 3, 1914.

Application filed December 27, 1913. Serial No. 809,113.

To all whom it may concern:

Be it known that I, STEWART E. SEAMAN, a citizen of the United States, residing in the borough of Brooklyn, county of Kings, and 5 State of New York, have invented a new and useful Improvement in Apparatus for the Destructive Distillation of Wood, of which the following is a full, clear, and exact description.

My invention relates to improvements in the art of the destructive distillation of wood and analogous substances. Heretofore the most general way of carrying on the destructive distillation of wood has been to place 15 the wood in a stationary retort until the wood is carbonized and its volatile or partly volatile contents driven out, or by carrying the material to be distilled by means of a conveyer through the retort. Rotary retorts 20 have also been experimentally used in this art, but there are difficulties in the way of carrying on any of the above systems. I have found by practical experience that it is necessary to carry on the destructive distillation 25 of wood or other analogous substances, in an atmosphere from which air is excluded, and while this is generally understood, and most forms of apparatus are presumably based on this theory, still in actual practice 30 a great deal of air is admitted into the retort with the material to be destroyed, with the result that the presence of oxygen causes combustion and often explosions, so that the apparatus is likely to be injured, the products 35 are liable to be expelled through the joints of the apparatus, and the distillate largely decomposed.

The object of my invention is to obviate these difficulties, and produce an apparatus 40 in which the continuous process of distillation can be carried on, in which the rotary parts can be kept sufficiently lubricated, the joints hermetically sealed, in which the volatile substances can be driven off and condensed, in which the non-condensable gases 45 can be utilized as fuel, in which the carbonized products can be conveniently withdrawn without danger of ignition and without special manipulation, and finally in 50 which the non-condensable gases can be utilized to force the air from the material which is being supplied to the retort so that the carbonization and distillation is carried on

in an atmosphere from which the oxygen is practically excluded. My invention has also 55 provided for the expansion of the retort without injury to it or accessory parts, and it also provides for a simple form of apparatus which is not likely to get out of order, and in which the parts are readily accessible 60 for cleaning and for repairs.

Another important object of the invention is to enable the apparatus to be worked efficiently and economically with very finely divided materials, such for instance as 65 saw-dust, which is practically a waste product and which contains, obviously, the materials to be distilled from wood in other forms. Heretofore it has been found very difficult to distill finely divided material like 70 saw-dust, because such material carries a great quantity of air, which it has been found difficult to eliminate before the material enters the retort, and furthermore as saw-dust is a good non-conductor, it is likely 75 to become packed, coated with a tarry substance which exudes from the wood under moderate temperature, and thus brought into such a condition that a portion of the quantity of saw-dust will resist ordinary efforts 80 of carbonization and distillation; but with my apparatus the material is kept divided and in an unpacked condition, and moreover the air is expelled before it enters the retort, so that perfect carbonization and 85 distillation results.

Reference is to be had to the accompanying drawings forming a part of this specification, in which similar reference characters indicate corresponding parts in all the views. 90

Figure 1 is a vertical longitudinal section of one end portion of the apparatus. Fig. 1^a is a vertical longitudinal section of the other end portion of the apparatus, the two figures when placed together showing the complete 95 apparatus. Fig. 2 is a diagram of the stationary head at the end of the retort. Fig. 3 is a cross section through the retort, Fig. 4 is a vertical section of the cooling bins in which the carbonized material is collected 100 from the retort. Fig. 5 is a diagrammatic plan of a part of the apparatus, and Fig. 6 is an end view of the retort with the connections in section.

In carrying out my invention I use a 105 relatively long rotary retort 10, which for

convenience is cylindrical, and which is carried by a rotary hollow shaft 11. The retort is mounted in a suitable casing 12 which can most conveniently be masonry, is provided with a suitable heating furnace 13, and with a stack 14 for the escape of the products of combustion in the furnace. The shaft 11 is provided with suitable bearings 15 at the ends of the retort, and is also provided at its ends with glands or stuffing boxes 16. The bearings 15 are supported on suitable posts 17 or equivalent supports, and these also support the stuffing boxes 16. The pipe 18 enters the upper end of the shaft 11, which it will be noticed is inclined, and the retort is also correspondingly inclined. The pipe 19 is adapted to carry a cooling medium such as steam or water, and a pipe 18 provides for the discharge of the heated water at the upper end of the shaft 11. This arrangement prevents the shaft from getting red hot and from being subject to too much contraction and expansion. The retort is provided with suitable strengthening spiders 20, the hubs of which are keyed to the shaft 11 as shown at 21 in Fig. 1^a, so that as the retort expands and contracts, it can slide on the shaft 11 without warping and without twisting the shaft.

The retort is provided with suitable blades 10^a so that when revolved it will stir up its contents and keep them in a finely divided state, and it will be seen that the contents of the retort will gradually work by gravity toward the lower end. The retort can be revolved in any suitable manner, and I have shown it provided with a suitable gear wheel 22 at its upper end, which meshes with the gear wheel 23 on the shaft 24, and the latter can be driven by any suitable means, as by a pulley 25, and can be carried in any suitable supports. The retort can also be stayed at necessary intervals as shown in Fig. 1^a, by providing it with a band or bands 26 resting on an idle wheel 27 mounted on a shaft 28 turning in suitable supports 29.

To prevent the retort from moving downward along the direction of its axis, it should have a suitable thrust bearing, and I have shown it provided with a fixed collar 30 running against rotary bearings 31 on an adjacent support. Obviously any suitable thrust bearing can be substituted for that shown.

The retort has stationary ends which provide for expansion, lubrication, and a tight joint, and this is a very important matter as heretofore in efforts along this line it has been found that the volatile products of carbonization have been apt to escape through the joints of the retort. As shown the cup-shaped head 32 at the upper end of the retort overlaps a flanged section 33, and a gland is formed between the two parts 32

and 33, and the face of the retort, which gland is filled with asbestos packing lubricated by graphite or similar lubricant, and connected with an oil cup 34. Thus the parts are well lubricated, and provision is made for the expansion of the retort longitudinally in the head without affecting the tightness of the joint. The head 32 is provided with a central opening 35 for the shaft 11, which opening can be suitably packed, and in the head I show also openings 36 and 37 the former being for the inlet of the material to be carbonized and distilled, and the latter for the exit of the volatile products. At the lower end of the retort a stationary head 32^a is arranged which connects with a flanged member 33 forming a joint substantially like that already described at the upper end of the retort, and the gland of the lower head is also connected with an oil cup 34.

The material to be distilled, which as stated should be saw-dust or finely divided wood or analogous material, is preferably fed to the apparatus through a hopper 38 (see Fig. 1) which is provided with a suitable gate 39 and discharges into the spiral conveyer 40 carried in the horizontal casing 41, and one end of the casing 41 can be provided with a suitable stuffing box 42 through which the shaft of the spiral conveyer extends, and this can be driven in any suitable manner, as by means of a pulley 43. It will be understood that while the spiral conveyer is most practical for this purpose, still any other suitable conveyer can be used either at this point or at other parts of the apparatus where spiral conveyers are shown, without affecting the principle of the invention.

The conveyer 41 discharges into a vertically arranged casing 44 which is provided with inclined ledges or baffles 45 and 46, the baffles 45 and 46 being preferably of opposite inclination so that the material will zigzag downward through the casing 44 and be broken up in its progress. This arrangement prevents the solid packing of the material, and also provides for the elimination of air as hereinafter described.

The casing 44 discharges into the casing 47 through which extends a spiral conveyer 48, and the casing 47 connects with the opening 36 in the head 32 so that the material is discharged from the casing 47 into the retort. The outer end of the casing 47 is provided with a suitable stuffing box 49, and I have shown a pulley 50 for driving the conveyer.

A gas outlet pipe 52 connects with the opening 37 so that the volatile products expelled by heating the material in the retort pass out through the pipe or casing 52, and this pipe is preferably made in two parts, meeting as at 53, for convenience in

assembling and disassembling, and the pipe is also preferably provided at its outer end with a removable cap 52^a to facilitate cleaning. The volatile products passing through the pipe 52 are passed downward through a connecting pipe 55 into the settling tank or trap 54, and to facilitate cleaning a short pipe 56 opens from the top of the pipe 52 in alignment with the pipe 55, and is provided with a suitable cap 57. The tank 54 is to collect the wood tar, and I have shown the tank provided with an over-flow pipe 58 and with a drainage pipe 59. By inserting the settling tank or trap between the retort and the condenser to be presently described, I am enabled to conveniently separate the tar, and it prevents the tar from fouling and clogging the condenser. A pipe 60 leads from the upper portion of the tank 54 to a casing or compartment 61, which is provided with vertical baffle plates 62 dropped from its top, and these baffles are arranged between the members of the inverted U shaped pipes 63 which extend upward into the casing 61 in which cold water or other cooling medium is kept. The distillate is drawn off through a goose neck trap 65, and I do not claim the condenser here shown as novel, nor do I limit my invention to this particular form of condenser.

Connected with the compartment 61 at the outlet end of the condenser is a pipe 66 through which the uncondensed gases pass, and the pipe 66 connects with branch pipes 68, 69 and 70, and delivers through the opening 67 and through the openings 67^a into the casing 44 beneath the ledges 45. This uncondensed gas is heavier than air, and as it backs up in the casing 44, it gradually passes around the lower ends of the ledges 46 and passes through the broken material dropping through the casing, carrying with it the greater part of the air, and the oxygen and mingled gases pass out through the pipe 72, a screen 71 being arranged within the casing 44 to prevent the more solid material from being withdrawn from the pipe 72. The pipe 72 is connected to a suitable exhaust fan 72^a or other exhausting means, and is arranged to discharge through the pipe 72^a and the opening 73 into the furnace 13, a suitable burner being here used for burning the gases.

It will thus be seen that I make my uncondensed gases form the very useful purpose of expelling the air from the material which is to be treated, and then utilize the mingled air and gases for fuel, and in practice these gases are almost sufficient to heat the retort 10.

The charcoal or other carbonized material is drawn off by gravity through the lower end of the retort, and the stationary head 32^a connects through a pipe 74 with a cas-

ing 75 in which is a spiral conveyer 77, the casing and conveyer being suitably supported as shown at 76. The conveyer 77 discharges into the inclined pipes 78 and 78^a, a suitable gate being arranged at the junction of the pipes so as to direct the carbonized material into the one desired, and these pipes deliver into bins 79 and 79^a having suitably controlled outlets 80. The bins are also provided with cooling coils 75 81 which serve to quickly cool the hot carbonized material. I have shown these coils within the bins, but obviously they could be placed outside the bins if desired.

It will thus be seen that I have provided a very simple and complete apparatus for carrying on the continuous destructive distillation of wood or analogous material, that ample provision is made for the expansion of the retort, that there is no chance for air in any possible quantities to enter the retort or for volatile gases to escape, and further that I provide a convenient means for separating the tar from the distillate, and for utilizing the uncondensed gases to expel the air from the material to be treated, and for furnishing a part of the fuel necessary to carry on the process. It will also be noticed that by having the exhaust drawing on the pipe 72 the effect is felt through all the connected parts back to the retort, and atmospheric conditions without vacuum or pressure, are maintained in the retort.

Attention is called to the fact that after the tar has been trapped off in the trap 54, and the gases have passed through the condenser 61, the uncondensed gases passing through the pipe 66 will be cool so that they can safely pass through the material as it is fed or sifted down through the casing 44. This is very important as were hot gases used, the charge in the feed casing 44 would instantly ignite or explode, owing to the combination of the hot gases and oxygen.

I claim:—

1. An apparatus of the kind described comprising a retort, means spaced apart from the retort and out of the zone of heat generated in the retort to feed material to the retort, and means for expelling the air from said material as it passes through the feeding means.

2. An apparatus of the kind described comprising a retort, means spaced apart from the retort for feeding the material thereto, and means for forcing cool gases through the material as it passes through the feeding means to expel the air from the material.

3. An apparatus of the kind described comprising a sealed retort, means spaced apart from the retort for feeding material to the retort, a condenser connected with the retort, and means for utilizing the cool un-

- condensed gases to expel the air from the material as it is fed to the retort.
4. An apparatus of the kind described comprising an essentially air tight retort, means for feeding material to the retort, said feeding means being inclosed in an air tight casing spaced apart from the retort, means for condensing the gases of the retort, and means for injecting the cool uncondensed gases into the casing which incloses the feeding means, thereby expelling the air from the material as it is being fed to the retort.
5. An apparatus of the kind described comprising a retort, means for feeding material to the retort, said feeding means being inclosed in an air tight casing spaced apart from the retort, means in said casing for breaking up and dividing the material as it is fed, and means for forcing a cool gas heavier than air through the said casing thereby expelling the air from the casing and the material therein.
6. An apparatus of the kind described comprising an essentially air tight retort, means for feeding material to the retort, an essentially air tight casing inclosing the feeding means, ledges or baffles arranged in the casing to break up the material which is being fed therethrough, means for condensing the gases generated in the retort, and means for conveying the uncondensed gases into the aforesaid casing thereby expelling the air therefrom.
7. An apparatus of the kind described comprising a rotary retort, means at one end of the retort for permitting the escape of gases, and at the opposite end for permitting the escape of carbonized material, means for feeding material to the retort, an air tight casing inclosing said feeding means, said casing comprising in part a vertically arranged portion, oppositely disposed ledges in the vertical portion of the casing, means for exhausting air from the casing, and means for admitting gases heavier than air to the casing.
8. An apparatus of the kind described comprising a retort having means at one end for the escape of gases, and at the opposite end for the escape of carbonized material, means for feeding material to the retort, an air tight casing inclosing the feeding means, means for exhausting air from the said casing, a condenser connected with the gas escape of the retort, and a connection between the condenser and the aforesaid casing whereby the uncondensed gases are discharged into the casing.
9. An apparatus of the kind described comprising a retort having means at one end for the escape of gases and at the opposite end for the escape of carbonized material, a furnace beneath the retort, means for feeding material to the retort, an air tight casing inclosing said feeding means and an air tight casing inclosing said condenser, an exhaust pipe connected with the casing and discharging into the furnace of the retort, a condenser connected with the retort, and a connection between the condenser and the aforesaid casing whereby the uncondensed gases are discharged from the condenser into the casing and from thence into the furnace.
10. An apparatus of the kind described comprising a rotary inclined retort having means at one end for the escape of gases and at the opposite end for the escape of carbonized material, a hollow shaft carrying the retort, a sliding connection between the body of the retort and its shaft, and means for passing a cooling medium through the hollow shaft.
11. An apparatus of the kind described comprising a rotary retort having means at one end for the escape of gases and at the other for the escape of carbonized material, stationary heads for the retort, and a sliding lubricated joint between the heads and the body of the retort, thereby providing for longitudinal expansion of the retort.
12. An apparatus of the kind described comprising a rotary inclined retort, stationary heads at the ends of the retort, a sliding lubricated connection between the stationary heads and the body of the retort, means for feeding material through the head at the upper end of the retort, means extending through said head at the upper end of the retort for permitting the escape of gases, and means for passing material through the head at the lower end of the retort.
13. An apparatus of the kind described comprising a rotary air tight retort having a stationary head at its upper end, means for feeding material through said upper head, a condenser, a pipe connection between said upper head and the condenser, and a settling tank or trap forming an element of said pipe connection.
14. In an apparatus such as described, the combination with the rotary retort and the condenser for condensing the gases generated in said retort, of a pipe connection between the retort and condenser, and a settling tank or trap forming an element of said pipe connection.
15. An apparatus such as described comprising a rotary inclined retort, means for feeding material into the upper end of said retort, an air tight casing inclosing said feeding means and provided with an exhaust pipe, oppositely disposed ledges arranged in a vertical portion of the said casing, a condenser connected with the retort, and a pipe connected with the condenser and discharging beneath the aforesaid ledges.

whereby the uncondensed gases of the condenser are discharged beneath said ledges.

16. The combination with the rotary inclined retort, of a stationary head at the upper end of the retort, means for feeding material through said stationary head, a gas escape pipe connected with said stationary

head, a settling tank receiving the gases from said pipe, and a condenser connected with the settling tank.
